CLAIM

The ornamental design for flower shears, as shown and described

DESCRIPTION

FIG. 1 is a top view of the flower shears showing my new design with the handle in a closed position;

FIG. 2 is a bottom view thereof with the handle in an open position;

FIG. 3 is, with respect to FIG. 1, a right side view thereof;

FIG. 4 is, with respect to FIG. 1, a left side view thereof;

FIG. 5 is a front view looking immediately towards the blades thereof;

FIG. 6 is a rear view looking immediately towards the handles thereof; and,

FIG. 7 is an isometric view thereof.
